United States Patent Office

Des. 195,211
Patented May 14, 1963

195,211

GUN HOLSTER

Frank A. Stella, Lyndhurst, N.J., assignor to The Hubley Manufacturing Company, Lancaster, Pa., a corporation of Pennsylvania

Filed Mar. 16, 1962, Ser. No. 69,308

Term of patent 14 years

(Cl. D30—1)

FIG. 1.

FIG. 2.

FIG. 3.

FIG. 4.

FIG. 1 is a front perspective view of a gun holster, showing my new design.

I claim:

The ornamental design for a gun holster, as shown.
